C. WHITE,
COOLING SYSTEM.
APPLICATION FILED MAY 21, 1917.

1,277,512.

Patented Sept. 3, 1918.

Inventor

CHARLES WHITE

By *Watson E. Coleman*

Attorney

UNITED STATES PATENT OFFICE.

CHARLES WHITE, OF YODER, COLORADO.

COOLING SYSTEM.

1,277,512.

Specification of Letters Patent. Patented Sept. 3, 1918.

Application filed May 21, 1917. Serial No. 169,996.

To all whom it may concern:

Be it known that I, CHARLES WHITE, citizen of the United States, residing at Yoder, in the county of El Paso and State 5 of Colorado, have invented certain new and useful Improvements in Cooling Systems, of which the following is a specification, reference being had to the accompanying drawings.

10 This invention relates to certain improvements in cooling systems for internal combustion engines, and has relation more particularly to a system of this general character wherein water or the like is employed; and it is an object of the invention 15 to provide a novel and improved system wherein air is forced directly through the water for carrying off a certain percentage of heat absorbed by the water.

20 The invention consists in the details of construction and in the combination and arrangement of the several parts of my improved cooling system whereby certain important advantages are attained and the 25 device is rendered simpler, less expensive and otherwise more convenient and advantageous for use, all as will be hereinafter more fully set forth.

The novel features of the invention will 30 hereinafter be definitely claimed.

In order that my invention may be the better understood, I will now proceed to describe the same with reference to the accompanying drawings; wherein—

35 The figure is a diagrammatical view, partly in elevation and partly in section, of a system arranged in accordance with an embodiment of my invention.

40 As disclosed in the accompanying drawings; E denotes an internal combustion engine of any ordinary or preferred type and provided with a jacket J in communication with the upper portion of a radiator inlet through the connection C. The lower 45 portion of the radiator R and the jacket J have in communication therewith an outlet connection pipe O. It is thought to be self-evident that the system as hereinbefore referred to is of a well-known thermo-siphon

50 cooling system type.

P denotes an air pump of any ordinary

or preferred type and which is adapted to be driven in any desired manner, either directly from the engine or by a part operated thereby. The pump P has a discharge pipe 1 leading to the lower portion of the jacket J, at the side of the jacket remote from the radiator and a second or branch pipe 2 leading to the lower portion of the radiator R. It will be self-evident 55 that upon operation of the pump, air will be forced through the water within the jacket J, and through the water within the radiator R, and that such air will escape through the opening 3 in the radiator cap 4. 60

From the foregoing description, it is thought to be obvious that a cooling system constructed in accordance with my invention is of an extremely simple and comparatively inexpensive nature and is particularly well adapted for use by reason of the convenience and facility with which it may be assembled, and it will also be obvious that my invention is susceptible of some change and modification without material departure from the principles and spirit thereof and for this reason I do not wish to be understood as limiting myself to the precise arrangement and formation 70 of the several parts herein shown in carrying out my invention in practice, except as hereinafter claimed.

I claim:

In combination with an internal combustion engine provided with a water jacket 85 and a radiator, said radiator having its top portion and bottom portion in communication, respectively, with the top portion and bottom portion of said jacket, the top of the radiator being provided therethrough with 90 a constantly opened port, a source of air supply, and means leading from the source and discharging within the lower portion of the side of the water jacket remote from the radiator and the lower portion of the 95 radiator.

In testimony whereof I hereunto affix my signature in the presence of two witnesses.

CHARLES WHITE.

Witnesses:

IRA M. YODER,
GEORGE BURCKLY.
